(57) **CLAIM**

The ornamental design for an electronic device, as shown and described.

DESCRIPTION

FIG. 1 is a rear perspective view of my new design for an electronic device;

FIG. 2 is a rear elevation view thereof;

FIG. 3 is a front elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is an enlarged rear perspective view of a portion of FIG. 1.

The even length dashed broken lines in the figures illustrate portions of the electronic device that form no part of the claimed design.

The uneven length dot-dash broken lines in the figures represent an unclaimed boundary line and form no part of the claimed design.
